UNITED STATES PATENT OFFICE.

CHARLES E. BLECHSCHMIDT, OF CONNERSVILLE, INDIANA.

BOLT FOR BURGLAR-PROOF SAFES.

No. 863,584.

Specification of Letters Patent.

Patented Aug. 20, 1907.

Application filed May 20, 1907. Serial No. 374,669.

To all whom it may concern:

Be it known that I, CHARLES E. BLECHSCHMIDT, a citizen of the United States, residing in Connerville, in the county of Fayette and State of Indiana, have invented certain new and useful Improvements in Bolts for Burglar-Proof Safes, of which the following is a full, clear, and exact description, reference being had to the accompanying drawings, forming part of this specification.

- 10 My invention relates to a certain novel construction of bolt for burglar-proof safes, whereby the bolt or bolts may be able to resist the action of any powerful explosive employed to blow open the safe door; and the invention consists in the construction of the bolt from 15 a plurality of plates of suitable resilient material whereby the effect of the explosion instead of shearing off or shattering the bolt, shall permit the bolt to give momentarily under the explosive action, to return again to a normal position unshattered and in a normal 20 condition.

I have illustrated my improved bolt construction in connection with an ordinary circular manganese steel bank safe, but it will be evident that my improvement of bolt may be employed in the construction of any 25 safe where it is desired to obtain the resilient action hereinafter described:

In the drawings: Figure 1— is a front elevation of an ordinary circular bank safe. Fig. 2— is a central vertical section of same. Fig. 3— is a rear elevation of 30 the door of the safe. Fig. 4— is an enlarged detailed view in perspective of a small portion of the door showing one of my improved bolts.

1 is the shell of the ordinary circular bank safe, usually constructed, in a single piece, of cast manganese 35 steel, say three or more inches in thickness, and provided with the standard —2, for a base, with rollers —3—3 for convenience in moving the safe from place to place. A beveled circular opening is left in the front wall of the casting for access to the interior, and provided with a circular door —4 to fit the opening, and the joint between the door and the safe wall is usually a ground joint. The door is swung on an ordinary 40 crane hinge consisting of a yoke —5, pivoted on the pintle —6 secured on the exterior of the safe at the side of the door opening, and the inner ends of the yoke are pivoted on studs attached to lugs —7—7 secured to the door.

For opening and closing the door in the construction illustrated, I provide a tapered arbor —8 controlled by 50 handle —9 which passes through a central opening cast in the door and is secured to the circular plate —10 on the rear surface of the door. This plate 10 is pivotally connected by the curved links 11 to the bolts

12, these bolts passing through suitable slots in the bolt frame 13 which is cast, as a flange, integral with 55 the door. The movement of the arbor and the plate 10 is controlled by an ordinary permutation lock actuated by the handle or knob 14 in connection with the usual dial plate 15, or the bolts may be thrown by any other of the well known devices controlled in any 60 other well known way.

It will be understood that the particular kind of safe and the particular construction of door and locks for controlling same, have no part in the present invention, which relates to the construction of the bolt or 65 bolts employed to secure the door in place.

In Fig. 4, I have illustrated this novel construction of bolt, and it consists of a plurality of resilient plates 16—16 of the proper size and shape to form when placed on top of each other, a substantial bolt or fastening device of the size required. These plates 16 which are preferably made of spring steel, are merely laid on each other without being fastened together except where pivoted by the bolt 17 to the link 11. The bolt frame 13 is formed with the slot 18 through which the 70 spring plates are passed and by which they are held together. In order to obtain somewhat better results, I prefer to give a slight bend to these bolt plates as shown at 18, although this may not be necessary in all cases, and where it is not desirable to use the construction of bolt frame illustrated in the present case, with the slots through same for holding and guiding the bolt as an entirety the plates may be held together by a thin band of metal.

With bolts of the construction illustrated, the explosive force of any charge of nitroglycerin or other high explosive pumped in around the door, for the purpose of blowing the door open, causes the door to spring away from the safe walls a short distance against the resilient force of the bolts without shearing off or 80 shattering the bolts, so that they immediately spring back to normal position holding the door locked. Such is the resilient effect of the bolts, that no charge of high explosive which can be inserted around the door is sufficient to shatter the bolts.

Having thus described my invention what I claim as new and desire to secure by Letters Patent, is:—

1. A bolt for safes comprising a plurality of resilient plates of suitable material superimposed to form a resilient body of the size required for the purpose specified.
2. A bolt for safes comprising a plurality of spring, steel plates slightly bowed to give greater resiliency, said plates being superimposed to form a resilient body of the size required for the purpose specified.
3. In a bolt construction for safes, the combination with 105 the door, of a plurality of resilient plates of suitable material superimposed to form a resilient bolt with means for supporting and holding the bolt in alignment on the door.

4. In a bolt construction for safes, the combination with the door provided with a bolt frame on its inner surface, with slots in the frame, and a plurality of resilient plates of suitable material superimposed to form bolts, said bolts 5 passing through and held in position by said slots.

5. In a circular bank safe, the combination, with a circular door, provided with a flange on its inner surface to form a bolt frame, a rotatable plate mounted within said flange, with means for actuating same from without the 10 safe, a series of links pivoted on said plate; and a plurality

of resilient plates of suitable material superimposed to form bolts, with slots in the bolt frame through which said bolts pass and pivoted connection for said bolts to the outer ends of said links, whereby said bolts may be thrown to lock and release the door.

CHARLES E. BLECHSCHMIDT.
